CONTAINER CONSTRUCTION

Oscar W. Wentz, Long Island City, N. Y., assignor to United States Automatic Box Machinery Co. Inc., Boston, Mass., a corporation of Massachusetts

Application May 12, 1939, Serial No. 273,198

2 Claims. (Cl. 229—16)

This invention relates to container construction and more particularly to a container construction of paper, cardboard, or like material.

One of the objects of this invention is to provide a simple, efficient, economical and practical container construction made of a material like heavy paper, cardboard, or other fibrous or cellulose or like material. Another object is to provide a container construction that will be simple and inexpensive to manufacture and well adapted to meet certain kinds of uses, such as, for example, where the container body and its bottom should be tight but need not meet certain peculiar requirements of liquid-tightness, and the like, of other fields of container uses. Another object is to provide a container construction particularly adapted for handling bulk materials which may or may not be wet, also materials that are plastic in consistency, like ice cream, and the like, and that will be strong and durable and sufficiently tight or liquid-proof to meet the requirements of such materials, while at the same time maintaining simplicity and inexpensiveness of manufacture. Another object is to provide a container construction of the above-mentioned character that will be light, strong and durable. Other objects will be in part obvious or in part pointed out hereinafter.

The invention accordingly consists in the features of construction, combinations of elements, arrangements of parts, and in the several steps and relation and order of each of the same to one or more of the others, all as will be illustratively described herein, and the scope of the application of which will be indicated in the following claims.

In the accompanying drawing in which are shown several of the various possible embodiments of the mechanical features of my invention,

Figure 1 is a development or plan view of a blank out of which the container body may be formed;

Figure 2 is a perspective view showing the blank in certain stages of the folding operations performed on it;

Figure 3 is a side elevation of the container body; and

Figure 4 is a view as seen from the bottom in Figure 3.

Similar reference characters refer to similar parts throughout the several views in the drawing.

Referring first to Figure 1, I have there shown a blank illustratively of rectangular shape, being bounded by preferably parallel edges 20 and 21

and end edges 22 and 23, the latter being shown as broken away in order to indicate that the top or closure portion of the container body may be made up in any appropriate or suitable form.

5 The blank is made of a suitable material, preferably a paper product such as heavy paper, cardboard, or other analogous or fibrous or cellulose material, hereinafter termed simply "paper."

Intermediate of the parallel side edges 20 and 10 21 there extend across the blank two parallel score lines 24—26—28 and 25—27—29, and centrally thereof is outlined a bottom A by the score lines 26 and 27 and the transverse fold or score lines 30, 31, the bottom A being quadrangular and 15 illustratively square. Score lines 28, 31 and 29 thus encompass an end wall B and score lines 24, 30 and 25 encompass an end wall C, these being also quadrangular and where the ultimate container is not to be tapered for nesting or like 20 purposes, end walls B and C are preferably rectangular or square.

To each side of the end wall B are side wall portions E and F encompassed within the score line 28, edge 20, and an interconnecting score 25 line 32, and by score line 29, edge 21, and an interconnecting cut line 33, respectively; where the container body is not to be tapered, score lines 32 and 33 are straight-line extensions of the score line 31.

30 In similar manner, the end wall C has side wall extensions G and H excepting that the blank is cut along the line 34, which, with score line 35 is in line with the score line 30. Also, a diagonal line of cutting 36 extends from the upper right-hand corner of the side wall portion G to the upper right-hand corner of the bottom A and in a similar or symmetrical manner there is a line of cutting 37 extending from the lower left-hand corner of the side wall portion F to the upper 40 right-hand corner of the side wall portion H.

Thereby there is formed a triangular flap A¹ integral with the bottom and foldable about the score line 26, and a triangular flap A² integral with the bottom along the opposed edge or fold 45 line 27 thereof; also, triangular flaps E¹ and H¹ are integral extensions of the side wall portions E and H, respectively, being foldable about the fold line 32 and 35.

50 Preferably, but not by way of limitation, the quadrangle formed by the triangular flaps A¹ and E¹ is equal to the quadrangle of the bottom A, as is also the quadrangle formed by the triangular flaps A² and H¹.

In forming the container body, folding operations, as indicated in Figure 2, are carried on in

appropriate sequence after applying a suitable adhesive, as indicated in Figure 1, to the flaps A¹, E¹, side wall portion E, and flaps A² and H¹, and side wall portion H. The parts G, C and H as a unit may first be folded about the fold line 30 (see Figure 2), and the side wall portion G bent or folded to an appropriate extent about fold line 24 to bring the lower edge of the wall portion G, as viewed in Figure 2, into substantial coincidence with the fold line 26 of the bottom A, 10 whereupon the flap A¹ is folded upwardly about the fold line 26 against the lower portion of the side wall portion G, thus bringing into action the adhesive carried by flap A¹ which becomes secured to this side wall portion.

These folding operations may take place with respect to a suitable block of a volume and shape corresponding to those of the ultimate interior of the container body and the next folding steps may comprise a folding upwardly about the fold line 31 of the parts E, B and F as a unit, throughout about 90° where there is to be no taper in the container body; the side wall portion E is thereupon folded about score line 28 to bring its adhesive-bearing face against the outer face of part G and the outer face of flap A¹ which had already been adhesively secured to part G, flap E¹ projecting downwardly. In a similar manner side wall portion F is folded about score line 29 to bring its left-hand edge, as seen in Figure 1, into coincidence with the score line 27 of the bottom A, then flap A² is folded upwardly about score line 27 to bring its adhesive-bearing face against the outer face of portion F. Side wall portion H is then folded about score line 25 to bring its adhesive-bearing face against the outer faces of the now overlapped parts A² and F, leaving flap H¹ projecting downwardly, like flap E¹. Thereupon, flaps E¹ and H¹ are folded about their respective fold lines 32 and 35 up against the under face of the bottom A to which they become secured through the adhesive which they carry and against which they are laid and secured to appear as shown in Figure 4 in which it will be seen that, assuming, as in the preferred case, that the flaps are appropriately dimensioned with respect to the bottom A, the two triangular flaps E¹ and H¹ completely cover over the under face of the bottom A.

Thus, the bottom A becomes reinforced in several ways. For example, it may thus be given two thicknesses or two plies of the material, thus also to resist wear and tear better, but also, because the flaps E¹ and H¹ are integral with the side wall portions E and H, respectively, the latter parts take part in carrying the load or strain imposed upon the bottom A itself. Furthermore, this construction also reinforces the junction of the bottom A along its score lines or edges 26 and 27 to the composite side walls G—E and H—F, between the portions of which the upwardly extending flaps A² and A¹ (Figures 2 and 3) extend and are secured, and thus, if desired, flaps A² and A¹ may be made smaller and also the parts of which these composite side walls are made may individually be made smaller or given shapes to effect additional saving in paper or raw materials. But flaps A¹, A² become securely anchored between the two last of the respective side walls G—E, and H—F and thus aid the flaps E¹ and F¹, respectively, in transmitting the load on the bottom to the respective side walls.

As many possible embodiments may be made of the mechanical features of the above invention and as the art herein described might be varied in various parts, all without departing from the scope of the invention, it is to be understood that all matter hereinabove set forth, or shown in the accompanying drawing, is to be interpreted as illustrative and not in a limiting sense.

I claim:

1. A paper container made of a single sheet and comprising a four-sided bottom, two opposed sides of which are extended to form opposed end walls, the latter each having lateral extensions, juxtaposed lateral extensions being overlapped and adhesively secured together thereby to form opposed side walls, said bottom having flap extensions one at each of its two remaining sides and each flap extension being joined to said bottom throughout the length of the said side of the bottom, whereby said two remaining bottom sides form axes about which said flap extensions may be respectively folded, said flap extensions being folded about their respective said axes upwardly and respectively received in between and adhesively secured to the overlapped lateral extensions of said two side walls, the latter having flap extensions which are respectively complements to said two flap extensions of said bottom and which complement each other when folded respectively about the aforesaid axes and against said bottom, together matching the area of the latter, said side wall flap extensions being so folded against said bottom and adhesively secured to said bottom to cover over the latter and reinforce it throughout its area.

2. A paper container made of a single sheet and comprising a four-sided bottom, two opposed sides of which are extended to form opposed end walls, the latter each having lateral extensions, juxtaposed lateral extensions being overlapped and adhesively secured together thereby to form opposed side walls, said bottom having flap extensions one at each of its two remaining sides and each flap extension being joined to said bottom throughout the length of the said side of the bottom, whereby said two remaining bottom sides form axes about which said flap extensions may be respectively folded, said flap extensions being folded about their respective said axes upwardly and respectively received in between and adhesively secured to the overlapped lateral extensions of said two side walls, the outermost of each of said overlapped lateral extensions that form said two side walls having downwardly directed flap extensions which, where they respectively join the outermost of said overlapped lateral extensions, are of dimensions at least equal respectively to the lengths of said two remaining sides of said bottom and are folded about said respective axes against and adhesively secured to the under face of the bottom, whereby the two angles formed by the bottom and said two side walls are, throughout their respective apexes which are formed by said axes, at least double-walled, said two side wall flap extensions being together of an area completely covering over said bottom when adhesively secured thereto, thereby to make said bottom at least double-walled.

OSCAR W. WENTZ.
